United States Patent Office

Des. 196,392
Patented Sept. 24, 1963

196,392

COMBINED CONTAINER AND LID THEREFOR

Charles J. Politis, Athens, Greece, assignor to Illinois
Tool Works Inc., Chicago, Ill., a corporation of Dela-
ware

Filed Sept. 21, 1962, Ser. No. 71,796

Term of patent 14 years

(Cl. D58—12)

FIG. 1 is a perspective view of a combined container and lid therefor showing my new design;

FIG. 2 is a top plan view thereof;

FIG. 3 is a bottom plan view thereof;

FIG. 4 is a side elevational view thereof, all sides being identical; and

FIG. 5 is a fragmentary cross-sectional view thereof taken along line 5—5 of FIG. 2.

I claim:

The ornamental design for a combined container and lid therefor, as shown and described.
